Application September 26, 1955, Serial No. 536,538

1 Claim. (Cl. 40—106.52)

This invention relates to an animated sign or the like and particularly relates to a sign featuring the word "Fly," which is suitable for use by air line companies and the like.

Air lines frequently seek to promote travel by employing the word "Fly," sometimes by itself and sometimes followed by the name of the air line. Such signs are frequently flashed on and off to secure attention. In accordance with the present invention, an animated sign is provided which attracts attention by featuring the word "Fly" in two different forms, one of which suggests the actual take-off and flying; this is accomplished by alternately flashing two Y's in the word "Fly," one of which is conventional and the other of which suggests flight.

The sign of the present invention is particularly adapted to be made of neon or similar tubing, but it can also be made from strings of lights, either in the open or concealed behind translucent portions of the sign.

In the drawing forming a part of this specification, Figures 1, 2 and 3 illustrate different embodiments of the sign of the present invention.

In Figure 1, there is shown a preferred embodiment of the present invention. In accordance with this embodiment, the letters "F" 3 and "I" 5 are left on at all times. The "y," generally designated 7, is a lower case "y" wherein one of the arms 9 and the stem 11 form a single continuous line. The opposite arm 13 is of conventional configuration. In the second form of the "y," generally designated 7a, the "y" has been moved upwardly on a continuation of the line formed by parts 9 and 11, and the stem 11a has been foreshortened. The arm 9a is made substantially the same length as 9 and has been spread out so that it is slightly below horizontal. The arm 13a has also been spread out, but to a less degree than 9a. Thus, the point A has been moved on the line of 11—9 to point A'; but the stem 11a is inclined slightly to the left. The "Y" is thus spread out as much as possible while still retaining the appearance of a Y.

In use, the sign would first be flashed with the "y" 7 showing, and then the "y" 7 would be turned off and, simultaneously, the "y" 7a turned on. Ordinarily, the "y" 7a would be left on for a much shorter period of time than the "y" 7. For instance, the time for "y" 7 might be twice as long as the time for Y 7a, and the repetition cycle might be on the order of four seconds. The relatively longer duration of the conventional word "Fly" definitely furthers the readability of the word when

2

the Y is distorted. Thus, an attractive, moving sign is provided and since the arms of the "y" resemble wings in flight, there is an actual suggestion of take-off and flying in the sign, which carries out the theme of the sign. The larger the sign and the further the distance from which it is to be viewed, the longer the cycle should be. However, the relative times to the two forms remain the same.

Although Figure 1 illustrates a preferred embodiment of the present invention, it will be obvious that the exact configuration of parts need not be employed. One alternate embodiment is shown in Figure 2. In accordance with this embodiment, a conventional F, 3, is used as before, as well as the 1, 5. The 1, 5, may be lower case 1, as illustrated, or a capital L. In this embodiment, the Y 15 is a conventional capital Y, having a stem 17 and arms 19 and 21. The alternate form of the Y, designated 15a, has a foreshortened stem 17a, and spread out arms 19a and 21a. The operation of the sign is exactly the same as that described under Figure 1. It will be noted that in accordance with the embodiment of Figure 2, one of the Y's is slightly superimposed on the other Y, but since they are not turned on at the same time, this causes no difficulty. It will also be noted that point A has been moved to point A' along the line formed by 19.

In the embodiment illustrated in Figure 3, a capital L 5 is employed and a capital Y 15. In this embodiment, the alternate Y 15a has been moved along the right arm of the Y as before, but the point A' is considerably above the top line of the letters.

In all of the embodiments, the stem or arms or both of the "Y's" may or may not be shortened or lengthened, depending on the effect desired.

It is believed apparent from the above description that I have provided a novel and attractive sign suitable for use by air line companies and the like.

I claim:

40 An illuminated display device for use in advertising air travel comprising: a panel on which is mounted a verbal injunction to fly including neon tubes shaped to form the letters F, L and Y, a representation of an airplane formed by neon tubes located above the letter Y and generally in the form of a letter Y with the arms spread and the stem shortened, means to supply current to the letters F and L continuously, and means to supply current to the letter Y and the representation of the airplane intermittently whereby to associate in the mind of a viewer an air trip with the verbal injunction of a flight.
